UNITED STATES PATENT OFFICE.

GEORGE C. BARDONS AND GEORGE W. DRAKE, OF CLEVELAND, OHIO.

TURRET-LATHE.

SPECIFICATION forming part of Letters Patent No. 657,306, dated September 4, 1900.

Application filed May 8, 1900. Serial No. 15,960. (No model.)

To all whom it may concern:

Be it known that we, GEORGE C. BARDONS and GEORGE W. DRAKE, citizens of the United States, residing at Cleveland, in the county of 5 Cuyahoga and State of Ohio, have invented certain new and useful Improvements in Turret-Lathes; and we do declare that the following is a full, clear, and exact description of the invention, which will enable others 10 skilled in the art to which it appertains to make and use the same.

Our invention relates to improvements in turret-lathes; and the invention consists in an adjustable stop mechanism operating in connection with the rotating turret-head, as hereinafter described, and more particularly pointed out in the claims.

The object of the invention is to provide a turret-lathe with adjustable stop mechanism 20 for the turret-slide which will automatically stop the slide in its travel when each tool in the turret-head reaches its work and which will when the next tool in the turret-head is brought in line with the work set and fix 25 the stop to limit the travel of the slide for that particular tool, each tool having its independent stop operatively connected with the turret-head.

In the accompanying drawings, Figure 1 is 30 a longitudinal section on line 1 1 of Fig. 3 and showing only a broken portion of a lathe with the slide and turret-head mounted thereon. Fig 1^a is a detail view of the two-part-dog-actuating fingers. Fig. 2 is a cross-section and rear elevation looking to the left 35 from line 2 2, Fig. 1. Fig. 3 is a plan and sectional view taken on line 3 3 of Fig. 1, showing more particularly the eccentric arrangement of the grooves or notches and the 40 relative positions, as seen in plan, of their co-operating arms, upon which the stops are mounted. Fig. 4 is a plan sectional view on line 4 4, Fig. 1, and showing the operating and locking means for the turret-head. Fig. 45 5 is a side elevation from the opposite side of the machine, as seen in Fig. 1, and shows the means for throwing out the gear connections to stop the turret-slide from further traveling.

A represents the bed or frame of a lathe 50 upon which a turret-slide support B is mounted, the turret-slide C proper having ways at

each side in which guides 2 on the slide-support B extend. The slide-support B carries the mechanism for actuating the slide C back and forth and consists of the cross-shaft D, 55 having the pinion 3 fastened thereon, which meshes with a rack 4 on the slide C. Rotation of shaft D is had through either the hand-wheel E at the left of Fig. 2 or the gear 5 on the end of the shaft at the right. Gear 5 meshes with a worm 6, as seen more clearly in Fig. 5, and this worm is mounted on a short shaft, which is driven through pinion 7 at its outer end, meshing with the usual gear and power connections. (Not shown.) The 65 short shaft has its bearings in a hanger 9, which is pivoted at 8 to the slide-support B, and a link 10 is connected to the outer end of the hanger to hold the worm 6 in engagement with gear 5. The link 10 is held 70 suspended from the inner end of the pivoted latch 11 and is held in this position as long as the pin 12 at the outer end of latch 11 is engaged by a catch-bar 13, which is pivoted to the rear of the support B at 14, and a spring 75 15, socketed in the rear face of said support, bears against the bar 13 and keeps the catch end in engagement with pin 12. Then as the turret-slide is fed forward by pinion 3 and rack 4 one of the stop-screws F on slide C 80 (designated by 16 in this instance) comes in contact with pivoted catch-bar 13 when the slide reaches the extreme forward movement intended for the working tool in turret-head G and presses the bar end inward and releases 85 pin 12, which allows the inner end of latch 11 to drop by gravity through the connected weight of the hanger 9 and worm 6, and the worm is thus freed and disconnected from gear 5, thus cutting off the power and stopping the further forward movement of slide 90 C. The stopping operation as outlined is identical for all the stops; but only one screw F at a time is brought into play at each forward movement of slide C, the others remaining at the higher elevation, which miss striking the bar 13 after the single stop-bolt to be used has been selected and caused to drop to a line parallel with bar 13. The selection and dropping of any single stop-screw 95 is governed by the rotation of turret-head G and is dependent on the position of the tool 100

to be used. As is well known in the art, the turret-head G is provided with openings in its periphery, in which the roughing, shaping, finishing, or other tools are fastened and which when fed forward by the movement of slide C come in contact with the revolving object to be worked upon. Six of these tool-openings are shown in the turret-head G, although more or less can be had, if desired, and are, for the sake of comparison, intended to represent each as carrying a tool, although none are shown. Each tool in its opening has a corresponding stop-screw F and operating-lever F', six of which are also shown, and when each tool is brought in line to engage the work its corresponding lever F' is actuated and its stop-screw F is dropped into position to engage bar 13. The turret-head G is supported upon the top face of slide C and is rotated on vertical shaft 17 and is operated by the ratchet-wheel 19 at its lower end within slide C. Rotation is imparted to the ratchet-wheel 19 when the slide C is traveling back by reason of the post 20 on the arm 21, fixed to frame A, coming in contact with the ratchet and in this instance giving a one-sixth turn to the turret-head. When the turret-head has been rotated to position, a stop-screw-carrying lever F' is actuated, each of said levers F' having an engaging pin 22, which rides and interlocks in a notch or groove 23, made in the bottom face of the turret-head, and each pin 22 has its own notch 23 to match with it and with none of the others. The levers F are pivoted within slide C upon a common cross-shaft 24, located at about one-third the length of the arms from the pins 22, and the extreme end of the longer part of the levers engage notches in the vertical sliding bars F²—one for each lever F'. The lower ends of these bars are split, and the stop-screws F are threaded through both ends, and a clamp-screw 25 clamps the bolt F after an adjustment has been made. A spring-pressed pin in the top of each bar F², bearing against the casing 26, serves to keep the long end of the lever F' down and the short end supporting pin 22, up—that is, when the pin 22 occupies its groove 23. Normally only one of these levers F' is in this position, the others being held in the position required to lift the balance of the stop-screws F above the striking-line of bar 13, their pins 22 riding or bearing against the bottom face of turret-head G. To the end that only one of the pins 22 be allowed to occupy a notch 23 when the turret is rotated to bring a new tool into action and a new adjusted stop-screw F to stopping position, the notches 23 are arranged in an eccentric or spiral line in the bottom face of head G, and the pins 22 and ends of lever F' are set to one side of the axial line of the turret-head G and the longitudinal center of the slide C and are arranged so that as the slide is rotated and each successive notch 23 is brought to the pins 22 only one pin at each one-sixth revolution will fall in the

notch especially designed to receive it. This dropping in occurs when the tool opening in the face of the turret-head comes to working position at the front end of slide C. Each notch 23 is grooved in the circular form, as seen more clearly in the broken-away portion of the turret-head in Fig. 5, to allow the pin 22 to ride freely in and out as the turret is revolved. The notches being open to the bottom of the head dirt cannot accumulate to clog the action and prevent the pins from working freely, and all parts are hidden and covered from above for further protection. As a further improvement along this line the locking-bolt H, which works in connection with the other turret mechanism, is brought underneath the turret-head and inclosed within the slide C, and a circular flange 26', having notches 27, depends from the bottom of head G, and these notches are of the same number as the tool-openings in the turret. Before the turret is free to revolve, bolt H must be withdrawn from the notch in the ring or flange 26', and this is done when the slide C travels back and the lower section 28 of the pivoted-dog-actuating finger 29 strikes the rib 30 on part B, the rounded end of finger 29 working in the slot 31 of the bolt and forcing the same inward out of the notch. A spring 32, socketed in the slide C, bears against a lug on bolt H and serves to throw the same back in the notch when the lower section 28 is released from contact with rib 30 by the travel of slide C. It will be noticed that the bolt H in locking works from the center of the turret-shaft outward or against the inner face of flange 26', and this arrangement permits of the operation of these parts in a very small given space and, furthermore, protects the same from all possible harm or disarrangement from the outside, as well as giving a more finished appearance to the machine as a whole.

The latch 11 is supported on the end of a cross-shaft 33 and can be actuated to raise the hanger 9 by means of the lever 34 on the opposite end of the shaft at the left of the machine. Catch-bar 13 also has a handle 35 at this side to release the latch and throw off the power by disconnecting gears 5 and 6 independently of the stop-screws F.

An important advantage gained by this improvement is that each tool in the turret-head can be made to come into contact with the work at any predetermined point by merely adjusting the stop-screw F representing that tool, which will cause the slide C to stop where desired—that is to say, the travel of slide C can be limited or extended for each tool, or, in other words, the slide can be made to travel different distances for each tool.

What we claim is—

1. In a turret-lathe, a turret-head and the slide therefor, notches eccentrically arranged in the bottom face of said head, adjustable stops for said slide, levers for each of said stops operatively engaged by said notches,

means to operate said head and slide, and means to stop the travel of said slide by one of said stops, substantially as described.

2. In a turret-lathe, the turret-head and the eccentrically - arranged notches therein, the turret-slide and the levers and stops carried on said slide, means to rotate said turret-head and operate said slide, and mechanism to throw off the power by means of one of said stops and notches, substantially as described.

3. In a turret-lathe, a turret-head and a sliding support therefor, a series of notches eccentrically arranged in the bottom face of said head, pivoted levers on said slide having engaging end members for said notches and adjustable stops supported by said levers to limit the movement of said slide, substantially as described.

4. In a turret-lathe, a rotatable turret-head having a series of notches radially distributed and spirally and eccentrically arranged at its bottom, a sliding support for said head having engaging members arranged to enter said notches successively as said head is rotated, adjustable stops on each of said members to limit the movement of said slide-support, and means to rotate said head and operate said sliding support, substantially as described.

5. In a turret-lathe, a rotatable-turret-head

and a supporting-slide therefor, a circular depending flange at the bottom of said head having notches therein, a sliding bolt mounted in said slide and having a spring to press said bolt into said notches from the inner side of said flanges, and a finger pivoted on said slide to engage both the frame of the lathe and the bolt to release said bolt from the notches, substantially as described.

6. In a turret-lathe, a rotatable turret-head, and a supporting-slide therefor, a circular depending and notched flange at the bottom and a series of notches or grooves arranged eccentrically and spirally in the bottom of said head, a locking-bolt having unlocking-fingers for said notched flange, a series of pivoted levers supporting adjustable stops at one end and engaging members for said grooves at the other end, means to rotate said head, and mechanism to operate said slide having throw-off connections engaged by said stops, substantially as described.

Witness our hands to the foregoing specification this 27th day of April, 1900.
